Primary Examiner — Steven J Czyz

(57) **CLAIM**

The ornamental design for a bag for oxygen concentrating apparatus, as shown and described.

DESCRIPTION

This patent or application file contains at least one drawing executed in color. Copies of this patent or patent application with color drawings will be provided by the Office by request and payment of the necessary fee.

1. Bag for oxygen concentrating apparatus

1.1 : Front, Top, Right Side Perspective View

1.2 : Front Perspective View

1.3 : Rear Perspective View

1.4 : Left Side Perspective View

1.5 : Right Side Perspective View

1.6 : Top Perspective View

1.7 : Bottom Perspective View

1.8: Rear, Top, Right Side Perspective View

The red colored parts on the article depict portions of the article that form no part of the claimed design.
